UNITED STATES PATENT OFFICE.

FREDERICK C. TAYLOR, OF PHILADELPHIA, PENNSYLVANIA, ASSIGNOR TO FERNAND McCANN, OF SAN FRANCISCO, CALIFORNIA.

FRAMING DEVICE.

1,283,595.

Specification of Letters Patent.

Patented Nov. 5, 1918.

Application filed March 22, 1917. Serial No. 156,573.

To all whom it may concern:

Be it known that I, FREDERICK C. TAYLOR, a citizen of the United States, residing at the city of Philadelphia, in the county of Philadelphia and State of Pennsylvania, have invented certain new and useful Improvements in Framing Devices, of which the following is a specification.

My invention relates to a framing device for moving picture machines, and the object is to provide a simple and inexpensive device with which the framing of the picture on the film can be accomplished with great ease and comparatively no strain on the film.

With the above and other objects in view, the nature of which will more fully appear as the description proceeds, the invention consists in the novel construction, combination and arrangement of parts as hereinafter fully described, illustrated and claimed. In the accompanying drawings forming part of the application, similar characters of reference indicate corresponding parts in both views.

Figure 1 is a side elevation of a moving picture machine equipped with a framing device embodying my invention; and

Fig. 2 is a section on the line 2—2, Fig. 1. Referring to the drawings, *a* is the plate or bed on which the mechanism is mounted, to which is secured firmly the framing mechanism carrier *c²⁷* and which is in the form of a plate having a branch *c³¹* extending parallelly to the plate and rigid therewith preferably at the rear end. The plate *a* also carries constant feed sprockets *c¹⁹*, *c²⁰* disposed above and below, respectively, of the carrier *c²⁷*. The intermittent feed sprocket *c²⁵* is constrained to revolve with a shaft *e⁵* which bears in an arm *c³²*, one end of which is pivotally connected on the shaft *e²* which bears in the carrier *c²⁷*. The other end of the arm carries a threaded nut *c²⁸* which is hinged at the said end of arm. A rod *c²⁹* threaded in the nut has a bearing *c³⁰* on the plate *a*, which allows the rod to turn but prevents longitudinal movement of said rod relatively to the plate, whereby the arm *c³²* can be moved on its pivot, that is, on the shaft *e²*.

The shaft *e²* carries a gear *e³* and a star wheel *e'* constrained to revolve with the gear and which is turned intermittently by a pin wheel *e* also revolving in the carrier

c²⁷. The gear *e³* meshes with a gear *e⁴* which is constrained to revolve with the shaft *e⁵* and whereby intermittent motion is imparted to the sprocket *c²⁵*. The carrier *c²⁷* has curved slots *e⁶* formed on an arc, the center 60 of which is in the axis of the shaft *e²*, so that the shaft *e⁵* can move with the arm *c³²* by which said shaft is carried. The slots are formed in both the plate and the arm of the carrier *c²⁷*.

This arrangement provides a joint in the framing mechanism, which maintains a fixed relation between the star wheel and the pinion but which allows an up-and-down movement of the intermediate sprocket 70 without interfering with the proper engagement of the gears by means of which the intermediate sprocket is driven.

The film from the upper constantly driven feeding sprocket *c¹⁹* is threaded 75 through the framing gate *d*, the proper loop being provided above the framing gate. In leaving the gate the film is engaged with the intermediate sprocket *c²⁵* from where it is directed to the lower constant feed sprocket *c²⁰*, each of the feeding sprockets being provided with a proper guiding roller *c²¹* which maintains the film in proper engagement with the corresponding feeding sprocket, a suitable projector-lens *b* being located on 85 the plate *a* in alinement with the framing gate *d*, the shutter *c* being also mounted on the plate in operative relation with the projector-lens, motion being imparted to said constant feeding sprockets and shutter in 90 the well-known way. By manipulating the rod *c²⁹* the arm *c³²* is moved and in consequence the film advanced or retarded, and whereby the picture on a film is framed with the opening in the gate *d*.

I claim:

1. In a framing device for moving picture machines, a carrier, a gear revolvably mounted in the carrier, means in said carrier for imparting to said gear an intermittent motion, an arm pivotally mounted in the carrier so that the axis of its pivot is in alinement with the axis of the gear, means for moving the arm on its pivot, a shaft revolvably mounted in the arm, a sprocket on said 100 shaft constrained to revolve therewith, and a second gear constrained to revolve with the shaft and in mesh with the first-mentioned gear, said carrier having arcuate slots engaged by said shaft, the center of 110

curvature of said slots being in the pivot of the arm.

2. In a framing device for moving-picture machines, a revoluble pin wheel having a fixed axis, a star wheel driven by said pin wheel, said star wheel having also a fixed axis, an arm pivotally mounted on the axis of the star wheel, means for controlling the pivotal movement of the arm, a sprocket 10 revolubly mounted on the arm, and motion transmission means from the star wheel to the sprocket.

3. In a framing device for moving-picture machines, a pivotally-mounted arm, a 15 sprocket revolubly mounted on said arm, a

gear constrained to revolve with the sprocket, a second gear in mesh with the first and coaxial with the pivot of the arm, means for controlling the movement of the arm on its pivot, and means for revolving 20 said second gear having a stationary axis outside of the pivot of the arm.

In witness whereof, I have hereunto set my signature in the presence of two subscribing witnesses.

FREDERICK C. TAYLOR.
